REFRIGERATING APPARATUS

Francis I. Rataiczak, Dayton, Ohio, assignor to
 General Motors Corporation, Dayton, Ohio, a
 corporation of Delaware

Application February 19, 1941, Serial No. 379,646

10 Claims. (Cl. 62—115)

This invention relates to refrigerating apparatus and more particularly to the control of temperatures in a two-temperature refrigerator cabinet.

There has been placed on the market a type of refrigerator commonly referred to as a "Cold-Wall" refrigerator. This type refrigerator differs from conventional household refrigerators in that a partition is provided within the food storage chamber for dividing the interior of the chamber into upper and lower food storage spaces or compartments. In this type of refrigerator a secondary refrigerant circuit forming means has a portion thereof wrapped around the walls of the lower compartment and has another portion thereof disposed in contact or in intimate heat exchange relationship with an evaporator or freezer coil, located in the upper compartment, of a closed primary refrigerating system. In this type of refrigerator there is an automatically actuated means for normally maintaining the evaporator of the primary refrigerating system and consequently the upper food compartment between predetermined limits. The temperature of the lower compartment is dependent upon the temperature of the primary evaporator and is preferably maintained at a substantially constant higher temperature, or between predetermined higher temperature limits. There is also provided in this type refrigerator a manually actuated or adjustable means, commonly referred to as a "cold-control," for modifying the operation of the automatically actuated temperature control to vary the temperature of the primary evaporator from its normal predetermined limits in order to provide faster freezing of substances placed in the evaporator to be frozen or for lowering the temperature of the upper compartment. Therefore, when the temperature of the primary evaporator is lowered or varied by the manually actuated means or "cold-control," the temperature of the higher temperature lower compartment is also reduced. For various reasons this reduction in the temperature of the higher temperature lower compartment is not desirable and is detrimental to certain foods stored therein. I contemplate the provision of means, in a refrigerator of the type described, for maintaining the temperature of the higher temperature lower food storage compartment thereof at or between its preferred limits at all times and particularly when the temperature of the upper compartment or when the temperature of the evaporator of the primary refrigerating system is lowered by the "cold-control" device.

It is, therefore, an object of my invention to provide in a two-temperature refrigerating system for a household refrigerator, incorporating a primary refrigerating system and a secondary refrigerant circuit, a means for varying the temperature of the primary evaporator which means also simultaneously controls the temperature produced by the secondary circuit.

It is another object of my invention to provide a two-temperature refrigerating system with a single means for lowering the temperature produced by an evaporator of a primary refrigerating system and for simultaneously varying the effectiveness of the condensing portion of a secondary refrigerant circuit associated with the primary evaporator to maintain the temperature produced by the evaporator portion of the secondary circuit substantially constant.

In carrying out these objects, it is a still further and more specific object of my invention to provide for the control of the temperature produced by a secondary refrigerant circuit, associated with a primary refrigerating system which does not involve the use of valves in the circuit.

Further objects and advantages of the present invention will be apparent from the following description, reference being had to the accompanying drawings, wherein a preferred form of the present invention is clearly shown.

In the drawings:

Fig. 1 is a front view of a refrigerator cabinet having my invention embodied therein and showing the door to the food chamber thereof in open position;

Fig. 2 is an enlarged vertical sectional view of the refrigerator cabinet disclosed in Fig. 1, showing a secondary refrigerating circuit associated with the evaporator of a primary refrigerating system mounted in the cabinet;

Fig. 3 is a fragmentary sectional view of the refrigerator taken on the line 3—3 of Fig. 2, showing a temperature control for the secondary refrigerant circuit in a normal position;

Fig. 4 is a view similar to Fig. 3, showing the temperature control for the secondary circuit in an adjusted position; and

Fig. 5 is a fragmentary diagrammatic view of a portion of the single control for both refrigerant circuits associated with the refrigerator cabinet.

Referring to the drawings, for illustrating my invention, I have shown in Fig. 1 thereof, a refrigerating apparatus of the household type including a refrigerator cabinet 10, having metal outer walls 11 and an inner metal liner member 12, forming a chamber therein. Any suitable or

desirable insulating material 14 (see Fig. 2) may be located between the walls 11 and liner 12. The front wall 11 of cabinet 10 has an aperture therein registering with an aperture provided in the front of liner 12 to provide an access opening leading to the interior of the insulated chamber. This access opening is normally closed by an insulated door structure 15. The walls 11 depend below the insulated chamber and form a machine compartment 16 therebelow (see Fig. 2), which compartment may house a refrigerant compressing and liquefying unit of a primary refrigerating system. A glass plate partition 17 divides the insulated chamber into an upper food storage compartment 18 and a lower food storage compartment 19. The glass partition 17 is provided with a rubber or the like sealing gasket 21 at all four edges thereof and this gasket engages the three vertical walls of the liner 12 and the inner face of door 15. A primary evaporator or cooling element 23 is mounted in the upper food storage compartment 18 to cool the same and a secondary refrigerating circuit is associated with the cabinet 10 for cooling the lower food storage compartment 19. The evaporator 23 has a conduit connection 26 with the sealed motor-compressor 27 of a refrigerant compressing and liquefying unit located in the machine compartment 16, and another conduit connection 28 with a condenser 29 of the unit. Refrigerant evaporated within the cooling element or evaporator 23 of the primary refrigerating system is withdrawn therefrom, through conduit 26, by the compressor 27 to cause the evaporator to produce a refrigerating effect. The evaporated or gaseous refrigerant withdrawn from the evaporator is compressed by the compressor 27 and forwarded, by conduit 31, to the condenser 29 where it is cooled and liquefied in any suitable or desirable manner. Liquid refrigerant flows from condenser 29 through conduit 28 into the lower portion of evaporator 23 under the control of a restrictor device 32 interposed in the conduit 28. The motor and consequently the compressor, of the sealed unit 27, is started and stopped automatically in response to the temperature of evaporator 23 by a snap-acting switch represented by the reference character 33. Thus, I provide a thermostatic bulb 34 having a pipe connection 36 with an expandible and contractible bellows (not shown) located within the switch 33 for actuating same. Switch 33 controls an electric circuit leading from a power line to the motor-compressor unit 27 and including wires 37 connected to switch 33 and the wires 38 connected to unit 27 as is conventional in the art. The thermostat 34 being responsive to the temperature of evaporator 23, actuates the switch 33 to start and stop operation of unit 27 for maintaining the primary evaporator and consequently the upper food storage compartment 18 between predetermined low temperature limits. The automatically actuated switch 33 may be of the conventional or so called "cold-control" type having associated therewith a means for manually changing the setting of the mechanism therein to vary or lower the temperature of the evaporator 23, such, for example, as when faster freezing of a substance contained in a tray and placed in the evaporator is desired. For this purpose a rod extends through the housing of switch 33 and has a portion 41 thereof projecting forwardly of switch 33. A front cover plate 42 provided on evaporator 23 has an opening therein for the reception of a knob 43 which is secured to the

end of rod portion 41. This knob 43 has a pointer 44 (see Fig. 5) thereon registering with a dial containing suitable numbers provided on the evaporator front plate 42. Rotation of knob 43 into registration with any one of the numbers on the dial indicates the amount of modification imparted to the mechanism of switch 33 to thereby alter its normal setting to cause modified operating periods of unit 27 for reducing the temperature produced by the evaporator below its predetermined low limit. The rod has another portion 46 projecting rearwardly of the housing of switch 33 and extending through a bearing member 47 (see Fig. 2), provided on the rear wall 48 of evaporator 23. An arm 49 is rigidly secured to the end of the rod portion 46 for a purpose to be hereinafter more fully described. Switch 33 is normally set to maintain the evaporator 23 at temperatures below freezing in order that ice may be frozen at all times. The cooling of food compartment 18 at such low temperature causes frost to form on the primary evaporator 23 and also causes dehydration of the air and the maintenance of a low relative humidity within the compartment 18. It is desirable in the refrigerator disclosed to maintain the lower compartment 19, provided by the dividing partition 17, at a high temperature and high humidity and for this purpose I provide the refrigerator with a closed secondary volatile refrigerant circuit for cooling the compartment 19 as is conventional in such so-called "Cold-Wall" refrigerators. In order to cool the lower food storage compartment 19, the outer surface of liner 12 has serpentine conduit loops 51 of a secondary refrigerant circuit intimately secured thereto. The conduit loops 51 form an evaporator or a refrigerant evaporating portion for the secondary circuit and the uppermost loop thereof is connected by a conduit 52 to the upper portion of a goose-neck type of trap 53 formed in this conduit of the circuit (see Fig. 3). The trap 53 is connected to a condenser or refrigerant condensing portion of the secondary circuit which comprises a conduit loop 54 attached to a metal plate 55 (see Fig. 2) which is secured by screws in intimate thermal contact with a side wall of the primary evaporator 23. The goose-neck trap 53 prevents any liquid condensing in the condensing loop portion 54 of the circuit from draining directly into the conduit 52 of the evaporating portion of the circuit. The lowermost end 56 of the condensing portion of the secondary circuit is connected to a section of flexible tubing 57 (see Fig. 3), which tubing is attached to the lower portion of an upstanding pipe section 58. A second section of flexible tubing 59 has its one end connected to the lower end of pipe 58 and has its other end connected to a downwardly extending conduit portion 61 of the secondary circuit which forwards liquid refrigerant from the condenser 54 to the evaporating loops 51. The flexible tubing 59 is provided with a loop portion to permit upward movement of pipe 58 relative to conduit 61 in a manner and for a purpose to be presently described. A third section of flexible tubing 63 has its one end connected to the top of trap 53 and has its other end connected to the upper portion of the pipe 58. Volatile refrigerant evaporating in the loops 51 cools the walls of compartment 19 and maintains the interior of this compartment at a temperature above freezing. The interior of compartment 19 is inherently maintained between temperature limits in accordance with the normal

predetermined temperature limits of the primary evaporator 23 by association of the condenser of the secondary circuit therewith. The refrigerant after evaporating in loops 51 of the secondary circuit flows upwardly into the condensing loop 54 where it is condensed and liquefied by the low temperature of the primary evaporator. Liquefied refrigerant flows from the lower portion 56 of the condenser 54 through the flexible tube 57, lower portion of pipe 58 and downwardly through the flexible tube 59 to the liquid forwarding conduit 61.

It is desirable in this type of refrigerator to provide some means of maintaining the normal predetermined temperature limits within the lower food storage compartment 19 at all times irrespective of the lowering of the temperature of the primary evaporator 23 below its normal low temperature limit when faster freezing demands are placed thereupon. This will insure the maintenance of the high humidity within compartment 19 which is desirable for the variety of foods normally stored therein. Therefore, I provide a single means for varying the temperature of the primary evaporator 23 from its predetermined temperature limits and for also controlling the temperature of the secondary circuit when the temperature of the primary evaporator is so varied. This means is preferably in the form of a movable or adjustable trap which varies the effectiveness of the condensing portion 54 of the secondary circuit by immersing same or a part thereof with volatile liquid contained in the secondary circuit. In the present disclosure, the flexible tubing sections 57, 59 and 63 permit movement of pipe 58 relative to the stationary conduit portions 52 and 61 of the secondary circuit. It will be understood that by raising the pipe 58 to elevate one end of the flexible tubing 57, liquid refrigerant will be trapped in the condenser 54. If the condensing portion 54 of the circuit has a lesser volume than the volume of liquid refrigerant in the secondary circuit, then, if the tubing or conduit 57 is raised, the condensing portion 54 will gradually become filled with liquid refrigerant. When the condenser 54 is partially filled with liquid refrigerant its effectiveness is diminished and less refrigerant will condense therein. When the condenser 54 becomes entirely filled with liquid refrigerant, it is no longer effective to condense refrigerant therein. Consequently, the amount of refrigeration in the evaporating portion 51 of the circuit and of the lower compartment 19 will decrease or cease in relation to the effectiveness of condenser 54. When the one end of tubing or conduit 57 is lowered then the refrigerant in the secondary circuit can circulate normally and refrigerate the lower compartment 19. The single means of the present disclosure comprises a connection between the knob 43 of the "cold-control" switch 33 and a portion of the secondary refrigerating circuit to trap liquid of the circuit in the condenser thereof. This means includes a link 66 having its one end pivotally secured, as at 67, to the arm 49, mounted on rod portion 46 and having its other end secured, as at 68, to the closed top end of pipe 58. It will be noted that when the knob 43, of switch 33, is rotated in a counterclockwise direction (see Fig. 5) from its neutral position No. 1, indicated on the dial provided on the evaporator front plate 42, to the No. 7 position, the portions 41 and 46 of the rod associated with the switch are also rotated. Rotation of the rod portions 41 and 46 in addition to

altering the setting of the mechanism of switch 33, to cause the temperature of the primary evaporator to be lowered beyond its normal low temperature limit, also rotates the arm 49 which elevates link 66 and consequently simultaneously raises pipe section 58 of the secondary circuit. The end of the tubing section 57 secured to pipe 58 is also elevated above the condenser portion 54 or at least above the lowermost part thereof (see Fig. 4), to thereby trap liquid refrigerant in the condenser 54. Thus, the colder evaporator 23 is maintained the more the effectiveness of the condenser 54 of the secondary circuit is reduced in order to prevent the evaporator 51 of the secondary circuit from following the lowering temperature of the primary evaporator. When the knob 43 is returned to its normal or neutral No. 1 position, after the desired period of low temperature of evaporator 23, the adjustable trap, comprising tubes 57, 59 and pipe 58, no longer exists (see Fig. 3), and the circulation of refrigerant in the secondary circuit occurs as usual in such systems. The amount of liquid refrigerant trapped in the condenser 54 from the remainder thereof in the secondary circuit depends upon the distance of upward movement of the pipe 58 and this movement depends upon the amount of rotation imparted to the knob 43 of switch 33 to anyone of its positions intermediate the No. 1 and No. 7 positions. Thus, the effectiveness of the adjustable trap provided in the secondary circuit to immerse the condenser thereof with volatile liquid depends upon the position of or the amount of rotation of knob 43. The decrease in the effectiveness of the condenser 54 takes place gradually in accordance with movement of the knob progressively from its No. 1 position to its No. 7 position. In other words, the colder the primary evaporator 23 is maintained, by the setting of knob 43, the more the liquid refrigerant will be trapped in the condenser of the secondary circuit to control or minimize the amount of refrigeration produced by the evaporating portion thereby so that the temperature of the high humidity compartment 19 remains substantially constant or between its normal predetermined limits. The purpose of the conduit portion extending from the juncture of the flexible tubing 57 with tubing 59 to the top of trap 53 and comprising pipe 58 and flexible tube 63 is to break any siphoning action of a column of liquid refrigerant within the secondary circuit that might cause liquid refrigerant to be siphoned out of the adjustable trap while it is being elevated or after elevation of flexible conduit section 57.

From the foregoing, it will be seen that I have provided an improved refrigerator of the household type, wherein one compartment within the refrigerator is cooled to a low temperature by a primary evaporator and another compartment therein is cooled to a higher temperature by a secondary refrigerating circuit associated with the primary refrigerating system located in the refrigerator. By providing the single means for modifying the temperature of the primary evaporator and for controlling the temperature produced by the evaporator portion of the secondary circuit, I insure the maintenance of a substantially constant temperature and humidity within the high temperature food storage compartment of the refrigerator. I have provided a secondary refrigerant circuit with a simple effective temperature control without the use of valves and which control is responsive to or actuated by the same means as is employed to vary the tempera-

ture of the primary evaporator with which the secondary circuit is associated.

While I have illustrated the single means of the present disclosure in a form which varies the effectiveness of the condenser of the secondary circuit, it is to be understood that other forms adapted to accomplish the desired results will become obvious and are all to be considered within the realm of my invention, and within the scope of the claims which follow.

What is claimed is as follows:

1. A refrigerating apparatus comprising, a primary cooling means normally maintained between predetermined temperature limits, a secondary circuit including a portion in heat exchange relationship with said primary cooling means and another portion adapted to produce a refrigerating effect, and a single means for varying the temperature of said primary cooling means from said predetermined temperature limits thereof and for maintaining the refrigerating effect produced by said another portion of said secondary circuit substantially constant when the temperature of said primary cooling means is so varied.

2. A refrigerating apparatus comprising, a primary cooling means normally maintained between predetermined temperature limits, a closed secondary refrigerating circuit containing a volatile fluid and including a condensing portion in heat exchange relationship with said primary cooling means and an evaporating portion normally maintained between predetermined temperature limits, and a single means for causing the temperature of said primary cooling means to be lowered below its normal predetermined low temperature limit and for maintaining the evaporating portion of said secondary circuit between its predetermined temperature limits when the temperature of said primary cooling means is so lowered.

3. A refrigerating apparatus comprising, a closed primary refrigerating system including an evaporator normally maintained between predetermined temperature limits, a closed secondary circuit containing a volatile liquid, said secondary circuit including a condensing portion in heat exchange relationship with a part of said primary refrigerating system and an evaporating portion normally maintained at a substantially constant temperature, and a single means for varying the temperature of the primary evaporator from said predetermined temperature limits thereof and for maintaining said substantially constant temperature of the evaporating portion of said secondary circuit when the temperature of said primary evaporator is so varied.

4. A refrigerating apparatus comprising, a closed primary refrigerating system including an evaporator normally maintained between predetermined temperature limits, a closed secondary circuit containing a volatile liquid, said secondary circuit including a condensing portion in heat exchange relationship with said primary evaporator and an evaporating portion normally maintained at a substantially constant temperature, and a single means for varying the temperature of said primary evaporator from said predetermined temperature limits thereof and for maintaining said substantially constant temperature of the evaporating portion of said secondary circuit when the temperature of said primary evaporator is so varied, said means consisting of means for varying the effectiveness of the condensing portion of said secondary circuit by im-

mersing at least a part thereof with the volatile liquid.

5. A refrigerating apparatus comprising, a closed primary refrigerating system including an evaporator normally maintained between predetermined temperature limits, a closed secondary circuit containing a volatile liquid, said secondary circuit including a condensing portion in heat exchange relationship with said primary evaporator and an evaporating portion normally maintained at a substantially constant temperature, and a single means for varying the temperature of said primary evaporator from said predetermined temperature limits thereof and for maintaining said substantially constant temperature of the evaporating portion of said secondary circuit when the temperature of said primary evaporator is so varied, said means consisting of means for elevating a part of said secondary circuit above at least a part of the condensing portion thereof to immerse said part of the condensing portion with the volatile liquid.

6. A refrigerating apparatus comprising in combination, a cabinet having a plurality of walls forming two food storage compartments therein, a closed primary refrigerating system associated with said cabinet and including an evaporator therein normally maintained between predetermined temperature limits for cooling one of said compartments, a secondary refrigerating circuit associated with said cabinet and containing a volatile liquid, said secondary circuit including a condensing portion in heat exchange relationship with said primary evaporator and an evaporating portion in heat exchange relationship with the other of said compartments and normally maintained at a substantially constant temperature for cooling said other compartment, and a single means for varying the temperature of said primary evaporator from said predetermined temperature limits thereof and for maintaining said substantially constant temperature of the evaporating portion of said secondary circuit when the temperature of said primary evaporator is so varied.

7. A refrigerating apparatus comprising in combination, a cabinet having a plurality of walls forming an upper food storage compartment and a lower food storage compartment therein, a closed primary refrigerating system associated with said cabinet and including an evaporator therein normally maintained between predetermined temperature limits for cooling said upper compartment, a closed secondary refrigerating circuit associated with said cabinet and containing a volatile liquid, said secondary circuit including a condensing portion in heat exchange relationship with said primary evaporator and an evaporating portion in heat exchange relationship with said lower compartment and normally maintained at a substantially constant temperature for cooling said lower compartment, and a single means for causing the temperature of said primary evaporator to be lowered below its normal predetermined low temperature limit and for maintaining said substantially constant temperature of the evaporating portion of said secondary circuit when the temperature of said primary evaporator is so lowered.

8. A refrigerating apparatus comprising, a closed primary refrigerating system including an evaporator normally maintained between predetermined temperature limits, a closed secondary circuit containing a volatile liquid, said secondary circuit including a condensing portion in heat

exchange relationship with a part of said primary refrigerating system and an evaporating portion normally maintained at a substantially constant temperature, and a single means for varying the temperature of the primary evaporator from said predetermined temperature limits thereof and for also varying the effectiveness of the condensing portion of said secondary circuit to maintain said substantially constant temperature of the evaporating portion thereof when the temperature of said primary evaporator is so varied.

9. In a refrigerating apparatus comprising a closed primary refrigerating system including an evaporator normally maintained between predetermined temperature limits and manually actuated means for causing the temperature of said evaporator to be lowered below its normal predetermined low temperature limit and also including a closed secondary fluid circulating system having a portion disposed in heat exchange relationship with a part of said primary refrigerating system for causing another portion thereof to produce a refrigerating effect, the method of maintaining the amount of refrigeration produced by said another portion of said secondary

circulating system substantially constant when the temperature of said evaporator is lowered below its normal predetermined low temperature limit by said means which comprises, altering the flow of fluid in said secondary circulating system simultaneously with and in response to movement of said manually actuated means.

10. A refrigerating apparatus comprising, a closed primary refrigerating system including an evaporator normally maintained between predetermined temperature limits, a closed secondary circuit containing a volatile refrigerant and including a condensing portion in heat exchange relationship with a part of said primary system and an evaporating portion, the construction and arrangement of said secondary circuit with respect to said primary refrigerating system being such that said circuit has a normal predetermined effectiveness, and a single means for varying the temperature of the primary evaporator from its predetermined temperature limits and for simultaneously acting on said secondary circuit to change its effectiveness for controlling the temperature of said evaporating portion thereof.
